US0D1079543S

(12) **United States Design Patent** (10) **Patent No.:** **US D1,079,543 S**
(45) **Date of Patent:** **** Jun. 17, 2025**

(54) **HEIGHT SAFETY TROLLEY RIGID RAIL**

(71) Applicant: **SAYFA R&D PTY LTD**, Boronia (AU)

(72) Inventors: **Murray Voss**, Boronia (AU); **Barry Voss**, Boronia (AU)

(73) Assignee: **SAYFA R&D PTY LTD**, Boronia (AU)

(**) Term: **15 Years**

(21) Appl. No.: **29/865,815**

(22) Filed: **Aug. 15, 2022**

(30) **Foreign Application Priority Data**

Jul. 27, 2022 (AU) 202214382

(57) **CLAIM**

The ornamental design for a height safety trolley rigid rail as shown and described.

DESCRIPTION

FIG. 1 is a perspective view of a height safety trolley rigid rail, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the height safety trolley rigid rail that form no part of the claimed design.

1 Claim, 6 Drawing Sheets
